TOY

Filed May 14, 1921

UNITED STATES PATENT OFFICE.

ATHERTON D. CONVERSE, OF WINCHENDON, MASSACHUSETTS.

TOY.

Application filed May 14, 1921. Serial No. 469,420.

To all whom it may concern:

Be it known that I, ATHERTON D. CONVERSE, a citizen of the United States, and resident of Winchendon, in the county of 5 Worcester and State of Massachusetts, have invented certain new and useful Improvements in Toys, of which the following is a specification.

This invention relates to an improvement 10 in toys and more particularly to the class of toys known as rocking horses.

The primary object of this invention is to devise a toy of the class described which will be collapsible, and capable of occupying the 15 minimum amount of space for convenience in shipping, and yet which may be readily and quickly set up to form a rigid structure.

With these and other objects in view the invention consists in providing a base portion 20 supported upon uprights carrying swings which in turn support standards upon which the body of the horse is mounted. The uprights attached to the frame are so constructed that they may fold inwardly alongside 25 of the longitudinals of the frame members to occupy no more space than the latter.

The standards supporting the horse proper are mounted upon blocks carried in the swings, so that when the horse is detached 30 from the standards, the block and standard may be folded parallel to the longitudinals and between the planes of the top and bottom thereof, which produces a most compact arrangement.

35 In the drawings:

Figure 1 is a side elevation of the preferred form of my invention set up.

Fig. 2 is a plan view of same.

Fig. 3 is a side elevation of the device in 40 its knocked down condition.

Fig. 4 is a plan view of same.

Referring now to the drawings, in which like numerals designate like parts throughout the several views, the reference character 45 1 indicates the longitudinals of the frame connected at the ends by members 2 having uprights 3 pivoted therebetween as at 4. The lower end of uprights 3 extends below the lower edge of members 1 and supports 50 the entire structure.

Additional braces 17 are provided attached to both longitudinals 1 and uprights 3, pivoted between its ends in the ordinary manner of braces of this construction, which

insures the parts 3 remaining in their upright position. 55

Pivoted to the upper inner face of members 3 are swings 5 of substantially U-shape. Supports 6, shown to consist of square blocks of a length corresponding to the width of members 5, are each provided with a longitudinal recess 7 on the under side thereof, which is adapted to receive the horizontal portion of the swing, said swing being secured therein by means of plates 8. 60

Standards 9 in the form of posts are secured to blocks 6 in any suitable manner and are adjustably socketed in members 10 which protrude from the under part of the horse body 11. Suitable holes 12 are provided in both standards 9 and sockets 10, which when aligned and a bolt or pin 13 passed therethrough, secures the horse to the base at any desired elevation, making the toy suitable for children of various ages. 75

The horse body 11 is preferably flat in order to occupy little space when knocked down. The saddle 14, which consists preferably of a piece of wood or the like of a greater width than the horse body, may be 80 removable for the same reason.

A readily removable foot rest 15 is provided, having cleats 16 transversely thereof, adapted to rest on longitudinals 1 to act as a partial support for the rider, and also to give 85 purchase in order to secure the swinging motion of a galloping horse.

When it is desired to fold this toy either for shipment or storage, the bolts or pins 13 are removed and the horse body taken from 90 the standards. The uprights 3 are then folded down between the longitudinals, the block carried by the swing taking a position in proximity to the end pieces 2, the standards extending toward the center of the toy. 95 The saddle is removed from the horse and the latter placed on top of the frame. It will thus be seen that the entire height of the folded article will be the height of the longitudinals plus the thickness of the horse body. 100

Various modifications will occur to those skilled in this art and may be practiced without departing from the spirit of my invention.

What I claim is:

A toy of the character described comprising a frame consisting of two spaced apart members, two uprights pivotally connected 105

to each end of said frame, swinging members carried by said uprights, standards mounted on said swinging members, a child supporting body carried by said standards, 5 said child supporting body being readily removable from said standards, said uprights being foldable downwardly between

the frame members, said swinging members being foldable between the uprights, so that said standards will occupy a position centrally and longitudinally of said frame. 10

In testimony whereof, I affix my signature.

ATHERTON D. CONVERSE.
